RING BOOK MECHANISM

Koloman Handler, Vienna, Austria, assignor to
 Messrs. Percy Jones (Twinlock) Limited,
 Bechenham, Kent, England

Application July 28, 1936, Serial No. 92,957
 In Austria February 29, 1936

3 Claims. (Cl. 129—24)

The application of the lever action for the closing mechanism instead of press studs, offers a very great advantage.

Further according to the invention, a spring is also provided by which the lever, the press stud or the like, is supported so as to prevent the same from shaking.

The drawing illustrates by way of example a construction of mechanical actuating device according to the invention.

In the drawing:

Fig. 1 is a perspective view of the ring book mechanism.

Fig. 2 a longitudinal section of the mechanism on line A—A of Fig. 3, when the mating prongs are closed to form rings and with the cover plate omitted, and Fig. 3 a cross section thereof on line B—B of Fig. 2.

Fig. 4 is a longitudinal section of the mechanism on the line C—C of Fig. 5 with the mating prongs parted so as to open the rings, and Fig. 5 a cross section thereof on line D—D of Fig. 4.

Figs. 6 and 7 represent the opening and closing levers.

The ring book mechanism consists of the usual resilient base plate 1 in which a pair of toggle connected ring plates 2 are inserted. The prongs 3 are fixed to the ring plates 2, and the prongs are parted and the rings formed by the prongs opened when the ring plates 2 are raised against the influence of the resiliency of the base plate 1 (Figs. 4 and 5) and the prongs are brought together and the rings closed when the ring plates are pressed down (Figs. 2 and 3). A cover 4 is further laid over the ring plates, and connected to the base plate 1. The ends of the ring plates 2 are provided with slots 5 for the engagement of bent over projections 6 of an opening lever 7 and a closing lever 8 while the lower end of the opening lever 7 carries an extension 9 directed upwardly, another similar extension 10 directed downwardly is provided on the closing lever 8 approximately in its center. To prevent shaking of the levers, one or both levers, 7 and 8, is or are provided with a spring 11, which presses against the lower side thereof and is with advantage bent out from the material of the base plate 1. In order better to distinguish the different duties of both levers, these may be either in different colors or distinguished by markings or the like for the opening and the

closing respectively. The operation of the device, according to the invention, is as follows:

When it is desired to open the ring book device for the purpose, for instance, of filing or removing sheets, pressure is simply exerted on the end of the opening lever 7 shown at the right hand end of Figs. 1, 2 and 4. This causes lever 7 to roll on the spring 11 and extension 9, which directly bears against the lower sides of the ring plates 2, thereby forces the latter upwards, 10 which after overcoming the springiness of the base plate 1, rise to the upper position (Figs. 4 and 5) and thereby part the prongs 3 and open the rings. When it is desired to again close the device, pressure is exerted on the closing lever 8 shown at the left hand end of Figs. 1, 2 and 4, whereupon the said lever rolls on the spring 11 and its extension 10 presses on the ring plates 2, and after overcoming the springiness of the base plate 1, the plates 2 are caused 20 to spring back to their lower position (Figs. 2 and 3), whereupon at the same time the prongs 3 are brought together in the form of a closed ring.

Having thus described the invention, I claim:

1. In ring book mechanism, a resilient base plate, a pair of ring-carrying toggle plates supported by said base plate to have movement toward and away from the base plate and arranged with slots adjacent one end, a closing lever at 30 said end having a convex under surface on which it rolls, two fingers which extend from one end of said lever and which are adapted to pass through the slots in the toggle plates and to act as supports about which the lever swings, the 35 opposite end of the lever extending from one end of the base plate and toggle plates, and a third finger on said lever adapted to engage the upper surfaces of said toggle plates and to exert a downward pressure thereon when the said 40 opposite end of the lever is pushed outwards and downwards to rock the lever.

2. In ring book mechanism according to claim 1, a part of the base plate below the closing lever severed to form a leaf spring which serves as 45 a resilient support for the convex under surface of the closing lever.

3. In book mechanism according to claim 1, a resilient member carried by the base plate and serving as a support for the convex under surface of the closing lever.

KOLOMAN HANDLER.
